UNITED STATES PATENT OFFICE.

JAMES M. MCGINTY AND THOMAS NOLAN, OF MOULTON, TEXAS.

IMPROVEMENT IN MACHINES FOR MAKING PLOW-IRONS.

Specification forming part of Letters Patent No. 136,444, dated March 4, 1873.

To all whom it may concern:

Be it known that we, JAMES M. MCGINTY and THOMAS NOLAN, of Moulton, in the county of Lavaca and State of Texas, have invented a new and useful Improvement in Machine for Forming Plow-Bars, of which the following is a specification:

Figure 1 is a front view of our machine. Fig. 2 is a side view of the same, showing the dies. Fig. 3 is a vertical detail section, taken through the line *y y*, Fig. 2. Fig. 4 is a horizontal detail section, taken through the line *x x*, Fig. 2. Fig. 5 is a view illustrating the method of cutting the plow-bars from the bar or plate.

Similar letters of reference indicate corresponding parts.

Our invention has for its object to furnish an improved machine for forming plow-bars which shall be simple in construction, convenient in use, and effective in operation, producing better bars at much less expense than when made by hand in the ordinary manner; and it consists in the combination of the driving-shaft, driving-wheel, segmental gear-wheel, intermediate gear-wheel, feed-roller gear-wheels, feed-rollers, crank or crank-wheel, and connecting-rod with each other and with the dies, for the purpose of operating said dies and feeding the bar or plate to them; in the dies provided with punches, spring-lifting bars and stops; and in the method of cutting the plow-bars from the bar or plate to avoid waste of stock and enable one set of dies to cut two plow-bars at each operation, as hereinafter more fully described.

A represents the frame-work of the machine, in bearings in the upper part of which revolves the shaft *B*, to which is attached the driving pulley or wheel *C*, to which the power is applied. To the shaft *B* is also attached a segmental cog-wheel, *D*, the cogs and blank space being so arranged that the bar or plate to be cut will be fed forward the required distance, and then allowed to be stationary while the dies are operating. The teeth of the segmental gear-wheel *D* mesh into the teeth of the gear-wheel *E* attached to the shaft *F* that revolves in bearings in the frame. The teeth of the gear-wheel *E* also mesh into the teeth of the gear-wheel *G* formed upon or attached to the upper

feed-roller *H*. The teeth of the gear-wheel *G* mesh into the teeth of the gear-wheel *I* attached to the lower feed-roller *J*. As the bar or plate from which the plow-bars are to be cut is fed forward by the rollers *H J*, it passes along the table *K*, between the guides *L* attached to said table, and which keep the said bar or plate in proper position to be operated upon by the dies. *M* is the lower or stationary die, which is secured to the table *K*. *N* is the upper or movable die, which slides up and down in ways *O* attached to the frame *A*. The die *N* is moved by the connecting-rod *P*, the lower end of which is pivoted to said die *N*, and its upper end is pivoted to the pin of a crank or crank-wheel, *Q*, formed upon or attached to the end of the shaft *B*. The dies *M N* are so formed as to form two plow-bars at each operation. Each die is provided with two punches, *R*, to form the holes in the plow-bars. Each die is provided with holes to receive the punches of the other die, and which extend out to carry off the plugs. The plow-bar is lifted off the punches of the lower die by two pivoted bars *S*, which are provided with springs *T* to raise the plow-bar, and which are so arranged that they cannot raise the plow-bar above the level of the table *K*, so that it may be pushed from the machine by the bar as it is fed forward by the rollers *H J*. The plow-bar is held while the upper punches are withdrawn by a stop or stops, *U*, attached to the frame *A*, and which, when the upper die descends, enter a notch in it, as shown in Fig. 3. The piece cut out between the curved edges of the bridges is held down when the upper die rises by two stationary pins or stop-rods, *V*, attached to the frame *A*, and which pass down through holes in the upper die *N*. The plow-bars are cut from the bar in the manner shown in Fig. 5, so that there is scarcely any waste of stock.

When the die *N* descends the first time after a bar is fed into the machine it forms the whole of one plow-bar and all the second one but separating it from the bar. The second time the die *N* descends it cuts off the second plow-bar, wholly forms the third, and forms the fourth all but cutting it from the bar, and so on until the bar is cut up.

Having thus described our invention, we

claim as new and desire to secure by Letters Patent—

1. The combination of the driving-shaft B, driving-wheel C, segmental gear-wheel D, gear-wheel E, feed-roller gear-wheels G I, feed-rollers H J, crank or crank-wheel Q, and connecting-rod P, with each other and with the dies M N, substantially as herein shown and described, for the purpose of operating said dies and feeding the bar or plate to them, as set forth.

2. The dies M N, provided with punches R, spring-bars S T, and stops U V, substantially

as herein shown and described, and for the purpose set forth.

3. The method of cutting the plow-bars from the bar or plate to avoid waste of stock and enable one set of dies to cut two plow-bars at each operation, as set forth.

JAMES M. McGINTY.
THOMAS NOLAN.
